WILLIAM S. JOHNSON, OF HENDERSON, KENTUCKY.

Letters Patent No. 73,530, dated January 21, 1868.

IMPROVEMENT IN BUGGY-TAPS.

The Schedule referred to in these Letters Patent and making part of the same.

TO WHOM IT MAY CONCERN:

Be it known that I, WILLIAM S. JOHNSON, of Henderson, Henderson county, Kentucky, have invented a new and useful Improvement in Buggy-Taps; and I hereby declare the following to be a full, clear, and exact description thereof, reference being had to the accompanying drawings, making part of this specification.

My invention consists in a provision whereby the "tap" may be at all times set, and firmly held to such degree of proximity to the boxing, as, on the one hand, to avoid undue friction, and, on the other hand, to avoid all jostling and rattling of the parts; and this, whether the washers be new or nearly worn out. In the accompanying drawings—

Figure 1 shows the axle-arm by side elevation, and the other parts in axial section.

Figure 2 is a perspective view of the tap, with another form of temper-screw.

A is an axle-arm or journal, terminating at its outer and inner ends, respectively, in the customary screw, B, and collar C. D is a customary bush or boxing. E is the nut or tap proper, adapted to screw upon the portion B. The screw-threaded orifice e, of the tap E, passes entirely through the latter, and receives a temper-screw, F, which, being set more or less forward into the tap, affords an adjustable shoulder or abutment for the tap, against the end of the axle-screw, and sets an exact and controllable limit to the advance of the tap. G and H are respectively the outer and inner washers.

The operation of my improvement is as follows: After the insertion of new washers, the temper-screw F is screwed just far enough inward to allow the tap to snugly confine the collar G, without pressing on it so tightly as to cause undue friction of the boxing either against the washers or axle. As the washers become worn, so as to loosen the boxing, the latter may be restored to its proper bearing by a slight retraction of the temper-screw, without the customary insertion of new washers, with their attendant binding and friction. One set of washers, on my plain, may be made to outlast several in the ordinary way, and perform better service, and with less injury to the parts. The temper-screw F cannot be easily lost, from jostling, because the pressure against the end of the spindle forces the threads firmly together, and holds both the screw F and the tap E securely in place.

I claim herein as new, and of my invention—

A buggy-tap, E, whose screw-threaded orifice, e, is prolonged to its outer end, and provided with a temper-screw, F, adapted to operate as set forth.

In testimony of which invention, I hereunto set my hand.
